(57) CLAIM

I claim the ornamental design for a bra, as shown and described.

DESCRIPTION

FIG. 1 is a front perspective view of a bra, showing my new design;

FIG. 2 is a front view thereof;

FIG. 3 is a left side view thereof;

FIG. 4 is a right side view thereof;

FIG. 5 is a top view thereof;

FIG. 6 is a front perspective view thereof showing the bra in a state of use with the outer panel decoupled from the inner panel;

FIG. 7 is a front view thereof;

FIG. 8 is a left side view thereof; and,

FIG. 9 is a right side view thereof.

The dot-dash broken lines represent boundaries of the claimed design and form no part of the claimed design. The broken lines depicting the remainder of the bra show features that form no part of the claimed design.

1 Claim, 9 Drawing Sheets
